BOWLING BALL ATTACHMENT

Chester M. MacChesney, Chicago, Ill.

Application June 3, 1942, Serial No. 445,550

4 Claims. (Cl. 273—64)

This invention relates to improvements in bowling ball attachments, and to the combination of such an attachment with a bowling ball, and its purpose is to provide an improved device for holding a bowling ball during the act of bowling without the necessity of inserting the thumb and fingers in the holes which are usually provided for this purpose. The present invention is an improvement upon that described and claimed in my prior United States Letters Patent No. 2,147,907, dated February 21, 1939.

In said Letters Patent there is disclosed a bowling ball attachment comprising a handle and one or more pneumatic devices by which the ball is gripped and held until released by the bowler. In the preferred embodiment, the attachment comprises a handle and one or more suction cups formed of rubber or the like and adapted to be pressed against the spherical surface of the ball to hold the ball by atmospheric pressure until the suction is relieved by the action of the bowler at the desired point in the swing or delivery of the ball. By the use of that invention it was possible to eliminate the usual holes in the bowling ball, thus bringing about a better balance of the ball and a saving in the cost of the manufacture thereof, while at the same time removing one of the most objectionable features of the sport of bowling, namely, the tendency of the fingers of the bowler to become sore and tender from frictional contact with the edges of the holes in the bowling ball. That bowling ball attachment has proven to be very efficient and satisfactory in use.

The principal object of the present invention is to provide an improved bowling ball attachment of the type referred to in which the handle and one or more attached suction cups are formed as one integral member by a process of molding a flexible plastic material, such as Vinylite, which has sufficient flexibility and resiliency to permit the suction cups to be pressed into gripping engagement with the ball and sufficient hardness and stiffness to permit the formation of a handle having the necessary rigidity. It has been found that flexible plastic materials of this type may be molded and the desired air passages therethrough formed with the use of cores of fragile material which may be broken up and removed after the molding operation is completed and the product sufficiently hardened. This integral bowling ball attachment, thus formed, has the advantage that it may be very economically and quickly formed and, in addition, the further advantages of durability in use and freedom from air leakage which enable it to be used for long periods of time and without danger of unintentional release of the ball at improper times. These and other features and advantages of the invention will appear more fully hereinafter.

The nature of the invention will be understood from the following specification taken with the accompanying drawing in which one embodiment is illustrated. In the drawing,

5 Figure 1 shows a side elevation of a bowling ball and of the improved attachment of the present invention illustrated in operative relation thereto while being held by the hand of a bowler;

10 Fig. 2 shows a top plan view of the structure illustrated in Fig. 1;

Fig. 3 shows a sectional view taken on the line 3—3 of Fig. 2;

15 Fig. 4 shows an end elevation of the bowling ball attachment illustrated in Figs. 1 and 2, looking toward the right as viewed in Fig. 1; and

Fig. 5 shows a bottom plan view of one of the suction cups, illustrating the check valve which is preferably employed in the bottom of each cup.

20 As illustrated in the drawing, the invention is embodied in an attachment 10 illustrated as being employed with a spherical bowling ball 11 which may be of the usual weight and formed of the usual material, preferably without the provision of the usual holes for engagement by the fingers 25 of the bowler. The attachment 10 comprises a handle 12 adapted to be gripped by the hand 13 of the bowler and this handle comprises two integrally formed downwardly extending arms 14, each of which is, in turn, formed integrally with

30 one of the two suction cups 15. The cups 15 are formed with their external surfaces in the shape of cones and the arms 14 are turned inwardly toward each other at their lower ends so that the axes of the two cups converge toward the center 35 of the ball when the device is applied thereto.

The cups 15 are concaved on their inner faces to form surfaces 15^a which have the form of segments of identical spherical surfaces formed with a substantially lesser radius than that of the ball 11. These two cavities in the cups 15 are connected through the handle 12, the arms 14 and the top portions of the cups 15 by a continuous 40 passage 16 which is preferably centrally located in these members. At one end of the handle, the 45 passage 16 communicates with a branch passage 17 which extends through a laterally projecting thumb-piece 18 formed integrally with the handle, the passage 17 opening to the atmosphere through a port 19 positioned on the upper surface 50 of the handle so that it may normally and conveniently be closed by the thumb 13^a of the bowler. Of course, the direction in which the thumb-piece extends will depend on whether the 55 bowler is right-handed or left-handed. The cups 15 have their outer conical surfaces 15^b so shaped that the walls of the cups decrease in thickness toward their outer annular edges where their inner and outer surfaces are separated by annular end surfaces 15^c located in planes extending at 60 right angles to the axes of their respective cups.

With this formation of the attachment 10, its handle 12 may be seized by the hand of the user who will place his thumb over the port 19 and then press the cups 15 downwardly against the surface of the ball. This will result in flattening the cups against the ball and expelling the air therefrom around the edges of the cups with the result that partial vacuums are formed within the cups and their inner surfaces conform more or less to the curvature of the ball. The ball is then firmly gripped by suction and will continue to be held until the partial vacuum within the cups is relieved by removing the thumb from the port 19 and thereby admitting air at atmospheric pressure to the interiors of the cups.

In order to prevent the rarefied air in the device from surging back and forth from one cup 15 to the other through the passage 16, when the cups are applied to the ball, which might result in an increase of the pressure in one cup and a further rarefaction of the air in the other, to such an extent to cause one cup and then the other to be released from the ball under extreme conditions, the cups are preferably provided with central circular recesses 15^d which are concentric with the mouths of the passages 16 and with the axes of the cups, and these recesses are occupied by check valves 20 formed preferably of rubber or other flexible resilient material. Each check valve is in the form of a flat disk adapted to fit within the recess 15^d and thickened at its outer edge, as shown at 20^a, to form an annular upwardly extending stiffening rib and the outer margin of each recess is correspondingly increased in depth by providing an annular channel adapted to receive the rib. Each recess is further provided around its edge with an annular flange 15^e which extends inwardly beneath the disk 20 to define an opening 15^f which is less than the diameter of the disk. Each disk 20 is provided with an annular series of holes 20^b spaced outwardly from the axis of the disk but within the opening 15^f. These holes 20^b are normally closed more or less tightly by reason of the fact that the disks seat against the top walls 15^g of the recesses but when partial vacuums have been formed in the cups by pressing them against the ball with the thumb on the port 19, the subsequent removal of the thumb will admit atmospheric pressure to the passages 16 and 17 and thus cause the resilient disks 20 to be stretched and bowed downwardly to a sufficient extent to admit the atmospheric air through the holes 20^b and thus relieve the partial vacuum in each cup. As long as the thumb is retained on the port 19, the disks 20 remain on their seats and thus prevent any surging of the rarefied air from one cup to the other during the act of bowling. The disks 20 may be readily snapped into place in the recess 15^d and may be conveniently removed when desired.

All parts of the attachment 10 described above, except the check valves 20 which are preferably employed, are formed as one integral structure and this structure is preferably formed by molding it of a resilient flexible plastic material such as Vinylite, which may readily be molded in the fluid state and which has sufficient flexibility and resiliency to permit the cups 15 to be flattened sufficiently to grip the ball while retaining the capacity to return to their normal shapes when they are released from the ball. The passages 16 and 17 and the recesses 15^d may be formed by

fragile core material which may be broken and removed after the molding operation has been completed and the product hardened. The rubber disks 20 may then be snapped into place to complete the device which is then very rugged and somewhat resilient and flexible, particularly in the thinner portions of the cups 15.

In the use of the invention the bowler presses the attachment 10 downwardly upon the ball, with his thumb closing the port 19, until the cups 15 flatten out sufficiently to grip the ball. The attachment with the ball suspended therefrom is then carried to the alley and the ball is delivered by swinging it in the usual manner while retaining the thumb on the port 19. At the desired point in the swing the thumb is lifted, thereby admitting atmospheric air to the cups 15 and releasing the ball onto the alley.

Although one form of the invention has been shown and described by way of illustration, it will be understood that it may be constructed in various other embodiments coming within the scope of the appended claims.

I claim:

1. An attachment for a bowling ball comprising a handle connected at its ends with a pair of suction cups adapted to be pressed against said ball, said handle and said cups being formed integrally of molded plastic resilient material and having air passages therethrough communicating with said cups and provided with a port opening to the atmosphere, and check valves mounted in said cups to control the flow of air through said passages.
2. An attachment for a bowling ball comprising a handle connected at its ends with a pair of suction cups adapted to be pressed against said ball, said handle and said cups being formed integrally of resilient molded material and being provided with a passage forming a communication between said cups and with another passage forming a communication between said first-named passage and the atmosphere, said cups having recesses therein at the mouths of said first-mentioned passage, and valve members mounted in said recesses.
3. An attachment for a bowling ball comprising a handle connected at its ends with a pair of suction cups adapted to be pressed against said ball, said handle and said cups being formed integrally of resilient molded material and being provided with a passage forming a communication between said cups and with another passage forming a communication between said first-named passage and the atmosphere, said cups having recesses therein at the mouths of said first-mentioned passage, and flexible resilient disks mounted in said recesses and having apertures therethrough displaced from the mouths of said first-mentioned passage.
4. An attachment for a bowling ball comprising a rigid handle connected at its ends with a pair of flexible resilient suction cups adapted to be pressed against said ball, said handle and said cups having air passages therethrough communicating with said cups and provided with a port opening to the atmosphere, and check valve means mounted to control the flow through said passages to prevent the surging of air through said passages between said cups.

CHESTER M. MACCHESNEY.
